George Morgan

United States Patent Office.

GEORGE MORGAN, OF BROOKLYN, NEW YORK.

Letters Patent No. 105,359, dated July 12, 1870.

IMPROVED STONE-SAWING MACHINE.

The Schedule referred to in these Letters Patent and making part of the same

To all whom it may concern:

Be it known that I, GEORGE MORGAN, of Brooklyn, in the county of Kings and State of New York, have invented a new and useful Improvement in Machines for Sawing Stone, of which the following is a full, clear, and exact description, reference being had to the accompanying drawing forming part of this specification, and in which—

Figure 1 represents a partly-broken side elevation of a machine for sawing stone constructed in accordance with my improvement, and

Figure 2, a plan of the same.

Similar letters of reference indicate corresponding parts.

My invention embraces a novel combination of mechanical devices for suspending and regulating the feed of the saw-frame, and for running it up or down at different velocities, whereby a more effective control of and perfect action is secured for the machine.

Referring to the accompanying drawing—

A represents the main frame, and

B, the swinging or reciprocating saw-frame, that may be worked by a pitman in the usual manner.

C is the bed on which the stone rests.

The saw-frame B swings, by its radius-rods *a a*, on cross-shafts *b b*, carried by slides or blocks, *c*, that are arranged to travel up and down vertical grooves, *d*, made in the uprights of the main frame.

Connected with the cross-shafts *b b* are chains, *e e*, which pass up over pulleys, *f f*, on upper cross-shafts *g g*, that have their bearings on the main frame, said chains being continued from the pulleys *f f*, to pass in reverse directions from opposite sides of the machine, subject to a series or succession of turns, around drums, *h h*, fast on an intermediate cross-shaft, *D*, so that, on rotating the latter in opposite directions, the saw-frame B is raised and lowered in a uniform manner from both or opposite ends.

On this cross-shaft *D* is keyed a worm-wheel, *E*, made to gear with an endless screw, *F*, on a horizontal shaft, *G*, which, accordingly as it is rotated to the right or left, raises or lowers the saw-frame, and, when said shaft is not rotated, serves to hold the saw-frame in lock, or from descending by its weight, by the gear of the worm-wheel *E* with the screw *F*.

The shaft *G* is operated to allow of the heavy saw-frame, with its saws, descending, when at work on the stone, by multiplying gearing, consisting of a screw, *H*, on a branch cross-shaft, *I*, working into a worm-wheel, *J*, on the shaft *G*. This insures a slow and powerful motion to check or control the descent of the saw-frame, and, in conjunction with the wheel *E* and screw *F*, makes more perfect and secure the lock when the saw-frame is at rest or stationary as regards its descent.

The worm-wheel *J* is made to slide by a feather on the shaft *G*, so that it may be thrown out of gear with the screw *H*, for a purpose that will be herein-after named.

Downward feed of the saw-frame B, through the screws *H F*, worm-wheels *J E*, and chains *e e*, is effected in a regular manner by a pawl, *H*, pivoted, in eccentric relation, by a wrist-pin or connection, *i*, to a rotating driving-pulley, *L*, loose on a shaft, *M*, said pawl working into and over a ratchet-wheel, *N*, fast on the shaft *I*, to rotate, in an intermittent manner, said shaft in the necessary direction to permit of the descent of the saw-frame at intervals, as required.

The extent of such downward feed, each stroke or time, is regulated, as the quality of the stone or other circumstances may require, by a vertically-adjustable slide or prop, *O*, over which the pawl *K* plays, and on which it rests during its action, so that, as said pawl is reciprocated by the pulley *L*, the same is made to fall sooner or later, or remain for a longer or shorter period in gear with the ratchet-wheel *N*, according as the prop *O*, which may be adjusted by a set-screw and slot *k*, is raised or lowered, to give more or less rocking action to the pawl as it is reciprocated, and thereby to vary the extent of its feeding-gear or connection with the ratchet-wheel, the length of stroke communicated to which regulates the downward feed of the saw-frame. This forms a most simple and efficient means of accomplishing such end or purpose, with every provision as regards nicety of adjustment.

When it is required to run the saw-frame up or down with greater speed, as in bringing the saws down to the stone, or lifting them from it, the worm-wheel *J* is slid out of gear with the screw *H*, as represented in fig. 2, and the driving-belt shifted from the loose pulley *L* onto a fast pulley, *P*, on the shaft *M*, and one or other of two reversing bevel-wheels *Q Q'*, in sliding gear, with the shaft *M*, thrown, by a clutch-lever, *R*, into gear with a bevel-wheel, *S*, on the shaft *G*, accordingly as it is required to raise or lower the saw-frame.

What is here claimed, and desired to be secured by Letters Patent, is—

1. The combination of the adjustable prop *O* with the pawl *K*, the revolving wrist-pin or connection *i*, and the ratchet-wheel *N*, essentially as and for the purpose herein set forth.

2. The combination of the sliding worm-wheel *J*, the screws *I F*, the worm-wheel *E*, the shaft *G*, the bevel-wheel *S*, and the reversing bevel-wheels *Q Q'*, substantially as shown and described.

GEORGE MORGAN.
